UNITED STATES PATENT OFFICE.

ISAAC W. MILLER, OF ST. LOUIS, MISSOURI, ASSIGNOR TO MILLER STORE FIXTURE COMPANY, OF ST. LOUIS, MISSOURI, A CORPORATION OF MISSOURI.

SHOW-CASE CONSTRUCTION.

1,076,143.

Specification of Letters Patent.

Patented Oct. 21, 1913.

Application filed August 24, 1912. Serial No. 716,849.

To all whom it may concern:

Be it known that I, ISAAC W. MILLER, a citizen of the United States, and a resident of the city of St. Louis and State of Missouri, have invented a new and useful Improvement in Show-Case Constructions, of which the following is a specification.

This invention relates to show case constructions and more particularly to "knock-down" structures.

It has for its principal object to produce a simple corner post construction or connection for the front and end panels which has the requisite rigidity, yet is readily set up and taken down.

Other objects and advantages to be attained will hereinafter more fully appear.

The invention consists in the parts and in the arrangements and combinations of parts hereinafter described and claimed.

In the accompanying drawings which form part of this specification and wherein like symbols refer to like parts wherever they occur, Figure 1 is a fragmentary horizontal section through one end portion of a metal show case structure illustrating an embodiment of the invention; Fig. 2 is a fragmentary vertical section through the front panel and coöperating portions of the base and top of the case; Fig. 3 is a fragmentary vertical section through the back of the case; Fig. 4 is a fragmentary plan view of one of the rear corners of the base; Fig. 5 is a fragmentary vertical section of the lower portion of a rear post and adjacent portion of the base; Fig. 6 is a fragmentary plan view of one of the front corners of the base; Fig. 7 is a fragmentary perspective view of the outer member of one of the front corner posts; Fig. 8 is a fragmentary perspective view showing the inner member of one of the front corner posts secured to the front and end panels; and Fig. 9 is a fragmentary horizontal section showing a modification of the corner construction.

In Figs. 1 to 8, inclusive, the invention is illustrated as applied to an "all-metal" frame construction. The complete base on which the side panels are mounted is a rectangular open frame comprising the front rail 1, end rails 2 and rear rail 3; and as both ends are alike, only the portion of the case adjacent to one end is shown in the drawings.

The front rail 1 and end rails 2 are con-

structed alike. They each comprise a channeled strip of metal 4 whose inner vertical flange 5 is turned inward horizontally, as at 6, and whose outer vertical flange 7 is turned outward horizontally, as at 8. Inside of the channeled strip is another strip 9 which has one of its marginal portions offset, as at 10, to provide a seat for the flange 6 of the outer strip 4, and then turned downward, as at 11, in coöperative relation to the portion 5 of the latter, said portions 5 and 11 being welded, riveted, or otherwise secured together. The opposite marginal portion of the strip 9 is turned downward, as at 12, and then outward, as at 13, said portion 13 being secured to the body of the strip 4. The space between the portions 7 and 12 constitutes a groove or channel in which the bottom edge portion of the panel frame is seated. Over the outer edges of the front and end base rails are placed molding strips 14 whose base portions 15 extend entirely across the undersides of the rails.

The back base rail comprises a channeled strip 16, the marginal portions of whose flanges 17 are turned inward, as at 18. An inner strip 19 has its marginal portions flanged, as at 20, and then offset outwardly, as at 21, the base portions of the two strips 16 and 19, and the flange portions 17 and 21 thereof, respectively, being welded, riveted, or otherwise secured together. A member 22 which is made of a sheet formed substantially U-shape and inverted is fitted in the channel provided by the base members 16 and 19. The upper portion of this member 22 is reinforced by an angle member 23; and the lower portion is reinforced by a channel member 24 which is fastened to the base members 16 and 19 by screws 25. The back rail member 22 has a channel member 26 secured thereon whose flanges 27 constitute tracks for the rollers 28 of sliding doors 29. The upper edge portions of the doors 29 slide in guideways comprising inverted channel members 30 riveted to the under side of the back rail 31 of the top frame. The back rail of the top frame comprises a strip of metal bent into rectangular form 105 with its meeting ends 32 overlapping and riveted together. The lower inner corner portion of this top rail 31 is reinforced by an angle member 33.

The front and end rails of the top frame 110

comprise a strip bent at right angles as at 34 and 35, the portion 34 being flanged downward, as at 36, and then inward, as at 37; while the portion 35 is flanged inward, as at 38. The portions 35 and 36 have secured thereto oppositely disposed filler blocks 39 whose adjacent faces are in planes flush with the edges of the respective flanges 37 and 38. A molding strip 40 has one marginal portion offset as at 41, and welded or riveted to the portion 34 of the top rail member. At intervals corresponding to the location of the blocks 39 angle members 42 are secured on the inner side of the molding. 10 These members 42 are perforated and screw-threaded to receive securing screws 43 which are inserted through aligned perforations in the blocks 39 and the upper portion of the panel frame over which the top rail member is fitted. The offset portions 41 of the front and end top rail members, together with a like rabbeted portion 44 of the back top rail 31, constitute seats for the glass plate 45. 15 The rear corner posts comprise a strip 46 which has a portion turned at right angles, as at 47, the marginal portion being flanged, as at 48. Another portion of the strip is turned at right angles, as at 49, and 20 then offset inwardly, as at 50, and the marginal portion is flanged inward, as at 51. A second strip 52 has one marginal portion flanged, as at 53, and secured to the portion 47 of the first mentioned strip. The opposite marginal portion of the strip 52 is flanged, as at 54, and secured to the portion 50 of said first mentioned strip. The post thus constructed is seated in an enlarged portion 55 at the rear end of the groove of 25 the end rail of the base frame, and the lower end portions of the strips 46 and 52 are secured by screws 56 to the upstanding flanges 57^a of a member 57 which is riveted or otherwise secured to the base. 30 The front panel 58 and end panels 59 are made so that the inner corners of their meeting ends coincide so that they may be secured to an angle member 60. The panels are constructed alike and comprise hollow 35 metal frames 61 fitted with glass plates 62. In practice, one of the sides of the angle member 60 may be riveted or otherwise secured permanently to the end of one of the panels, as at 63, while the other side of the 40 angle member is detachably secured to the other panel member, as by screws 64. As shown in Figs. 1 and 8, the marginal portions of the angle member 60 are flanged, as at 65, and the sides of said angle member are preferably wider than the thickness 45 of the panel frames. An outer angle member 66 is provided at its inner side with an angle member 67 whose marginal portions are offset, as at 68, so as to overlap the flanges 65 of the angle member 60, or in

other words providing slideways 69 for said flanges 65. The marginal portions of the outer angle member 66 are flanged inward, as at 70, the edges just touching the outer faces of the front and end panels. The base 70 rails are cut out, as at 71, at the corners where the grooves that receive the front and end panels meet, so as to accommodate the lower end portions of these angle members 60 and 66. 75

In assembling the show case, the rear corner posts are first secured to the base. Then the end panels are placed on base with their lower edge portions seated in the grooves provided therefor in the end rails, 80 the rear vertical edge portions of the panels being projected into the hollow portions of the rear corner posts. The front panel is then placed in position and the angle member 60 is secured by the screws 64 to the front 85 or end panel as the case may be; the angle member being permanently secured to the other panel by the rivets 63. The outer angle member 66 is then slipped downward in engagement with the angle member 60. 90 After the parts are thus assembled, the top of the show case is placed over the upper edge portions of the panels and fastened by the screws 43. The side and end panels are secured to the base by screws 72 which 95 are inserted from the under side of the base rails.

As shown in Fig. 9, the meeting corners of the front and end panels may be mitered and fastened by angle brackets or clips 73 on the inner side. The outer face of the panels adjacent to the corners may be rabbeted to provide shoulders 74 over which an angle member 66^a may be slipped. The panels, as shown in this modification, comprise solid wooden frames, but it is obvious that the same corner arrangements are applicable to the hollow sheet metal construction as well. It is also obvious that the front corner arrangements illustrated and described in connection with the sheet metal structure of Figs. 1 to 8, inclusive, is applicable to a wooden show case structure, or to one of part metal and part wood. 105 110

Obviously, the construction admits of considerable modification without departing from the invention. Therefore, I do not wish to be limited to the specific construction and arrangement shown. 115

What I claim is:

1. In a show case, an end panel and a front panel, the ends of said panels meeting so that their inner corners coincide, and means for securing said panels together, said means including an angle member one of whose sides is fastened to the end of the end panel and the other to the end of the front panel, and a second angle member whose sides have a sliding engagement with said first mentioned angle member and overlap 120 125 130

and slidably engage the adjacent outer faces of said panels.

2. In a show case, an end panel and a front panel, the ends of said panels meeting so that their inner corners coincide, and means for securing said panels together, said means including an angle member one of whose sides is fastened to the end of the end panel and the other to the end of the front panel, the marginal portions of said angle member projecting beyond the outer corners of the respective panels, and a second angle member whose sides have a sliding engagement with the projecting marginal portions of said first mentioned angle member and overlap and slidably engage the adjacent outer faces of said panels.

3. In a show case, an end panel and a front panel, the ends of said panels meeting so that their inner corners coincide, and means for securing said panels together, said means including an angle member one of whose sides is fastened to the end of the end panel and the other to the end of the front panel, the marginal portions of said angle member projecting beyond the outer corners of the respective panels and being flanged, and an outer angle member whose sides are respectively arranged and adapted to slidably engage the flanged marginal portions of said first mentioned angle member.

4. In a show case, an end panel and a front panel, the ends of said panels meeting so that their inner corners coincide, and means for securing said panels together, said means including an angle member one of whose sides is fastened to the end of the

end panel and the other to the end of the front panel, the marginal portions of said angle member projecting beyond the outer corners of the respective panels and being flanged, and an outer angle member whose sides are respectively arranged and adapted to slidably engage the flanged marginal portions of said first mentioned angle member, the marginal portions of said outer angle member overlapping the outer faces of the adjacent end portions of said panels and being flanged inward so that their edges slidably engage the panels.

5. In a show case, the combination of two angularly disposed side panels whose inner corners of their meeting ends coincide, said panels being connected by an angle member whose sides are respectively secured to the adjacent end faces of the panels, and an outer angle member whose sides overlap the adjacent outer side faces of the panels and are detachably secured to said first mentioned angle member.

6. In a show case, the combination of two angularly disposed side panels, a member for securing the meeting ends of said panels together, and an angle member detachably secured to said securing member, the marginal portions of said angle member extending beyond said securing member and bearing against the adjacent outer faces of said panels.

St. Louis, Mo., Aug. 21, 1912.
ISAAC W. MILLER.
